UNITED STATES PATENT OFFICE.

JEFFERSON C. GIBSON, OF CHICAGO, ILLINOIS.

THERMOSTAT.

Application filed November 17, 1922. Serial No. 601,642.

The main objects of this invention are to provide an improved thermostat; to provide an improved construction and arrangement of the electrodes; to provide improved means for shiftably mounting one of said electrodes for the purpose of making and breaking the electric circuit; to provide improved mechanism for actuating said means; and to provide a device of this kind which is particularly adapted for use with a bimetallic band or a pressure-controlled element.

An illustrative embodiment of this invention is shown in the accompanying drawings, in which:

15 Figure 1 is a front elevation of a thermostat constructed in accordance with this invention, the cover for the lower end thereof being omitted for the sake of more clearly illustrating the arrangement of the electrodes and the shifting mechanism therefor.

20 Figure 2 is a vertical sectional elevation of the same taken on the line 2-2 of Figure 1.

25 Figure 3 is an enlarged sectional detail illustrating the manner in which the adjustable electrode is mounted on the base plate.

30 Figure 4 shows a modification of the electrode shifting mechanism for use with a pressure-actuated mechanism, a part of the housing therefor being omitted for the sake of more clearly illustrating the electrode shifting means.

35 A thermostat embodying this invention involves the use of a pivoted lever arm connected to a member arranged so as to be actuated by temperature or pressure changes for automatically swinging said arm to retract or engage electrodes in a circuit leading to a control device for the heating plant, 40 the connection between said member and lever arm being such that the shifting of the arm is effected rather suddenly, so as to insure a quick making and breaking of the circuit at said electrodes.

45 In the specific embodiment shown in Figures 1 and 2, the thermostat comprises a base plate 1, upon which is mounted a lever arm 2, and connected to and actuated by a temperature-controlled member 3, so as to 50 cause the relative shifting of electrodes 4 and 5 forming a part of an electric circuit leading to a control device for the heating plant. A shiftable indicator 6 is arranged to assist the tension of the member 3, and

a thermometer 7 is mounted upon the base plate for the purpose of indicating the temperature conditions.

The base plate 1 is preferably a metal casting of a size and shape to provide a suitable support for the various parts of the 60 thermostat.

The lever arm 2 is pivotally suspended on the base plate 1 at 8, so as to have a swinging movement in a plane parallel to that of the base plate 1. The construction 65 of lever 2 and the suspension thereof on the base plate, and the arrangement of the electrodes 4 and 5, are such that the lever arm 2 is normally urged by gravity to engage the electrodes 4 and 5. A slot 9 is formed 70 in the lever arm 2 near the lower end thereof, through which a pin 10 on the base plate 1 extends and coacts therewith for limiting the swinging movement of said arm. The head of said pin 10 projects 75 somewhat through the slot 9, as shown in Fig. 2, and as will be referred to.

When the shifting of the lever arm 2 is to be controlled by temperature changes, the member 3 is in the form of a bimetallic 80 spring of a more or less conventional type, the upper portion of which is looped upon itself, as at 11, with the end 12 of the member secured to the upper end of the base plate 1, either directly, where there is to 85 be no adjustment of the tension of said member, or to a lever 13, where the tension of the member is to be adjusted for causing the shifting of the electrodes to take place at different temperatures. The main 90 body part of member 3 below the loop 11, is arranged in front of the lever arm 2 and disposed in substantially longitudinal alignment therewith. The member 3 terminates at its lower end near the lower end of the 95 lever arm 2, and is connected to said lever arm by a helical spring 14, the upper end of which is hooked into the end of the member, and the lower end of which is connected to a pin 15, secured near the terminus of the 100 lever arm 2. A short rod 16 is embraced within the spring 14 but otherwise unconnected thereto and unconnected to the lever arm 2 and the member 3. This rod stiffens the axis of the helix 14 and serves to more 105 positively insure frictional engagement of spring 14 with the head of pin 10. This friction supplements gravity to retard open-

ing of the switch contacts until the thermostat has developed sufficient tension to insure snap action in opening.

The electrodes 4 and 5 are made from a suitable metal, such as silver, which does not readily fuse when electrodes are disengaged, and are welded or otherwise secured to the ends of threaded rods 17 and 18, respectively. The rod 17 is secured to the lower end of the lever arm 2, being properly insulated therefrom and connected by a flexible conductor 19 to a binding post 20 on the base plate 1. The rod 18 is supported on insulating washers 21, set in a lug 22 formed on the base plate 1, the rod being secured in place by means of nuts 23, which are screwed up against the insulating washers 21. A flexible conductor 24 is secured to the end of the rod 18 and leads to a suitable source of electricity, as does also another conductor (not shown) connected to the binding post 20.

The adjusting indicator 6 comprises a pointer 25 integrally formed on the upper end of the lever 13, which lever is pivoted at 26 to the base plate 1, so that the shifting of the pointer 25 across the scale 27 draws on the end 12 of the member 3, so as to contract or enlarge the loop 11, and thereby alter the spring tension of the member 3 and its consequent sensitiveness to temperature changes. A thermometer 7 of the usual form, is mounted on the base plate 1, in front of the other parts just described, so as to be readily visible for the purpose of indicating the temperature condition of the room wherein the thermostat is used.

A suitable cap (not shown) is adapted to be placed upon the lower part of the base plate 1, for the purpose of enclosing the mechanism below the thermometer 7. To this end, the base plate is provided with an aperture 28 to receive a lug on said cap, and with a spring 29 adapted to yieldingly engage the cap and hold it in place.

With the modification shown in Figure 4, the general arrangement of the parts is more or less the same as in the modification shown in Figures 1 and 2, with the exception that the arrangement is inverted. In this form the member 3 is a bell crank lever pivoted at 30, with the upper end of the vertical arm connected to the lever arm 2 by means of the spring 14. The other arm of the bell crank lever carries a weight 31 adjustable along the length thereof, for the purpose of varying the sensitiveness of the device. The member 3 is actuated by the diaphragm device 32, the stem 33 of which engages the horizontal arm of the member 3.

The operation of the device herein shown and described, is substantially as follows:—

The rod 18, carrying the electrode 5, is first adjusted so that at a temperature below

that desired in the room in which the device is to be used, the lever arm 2 normally engages the electrodes 4 and 5, thus closing the circuit leading to the control device for the heating plant. The position of the parts is shown in Figure 1, where it will be observed that the extreme lower end of the member 3 is slightly to the right of the longitudinal center line of the lever arm 2, and the axis of spring 14 is inclined to the longitudinal axis of the member 3 and the longitudinal center line of the lever arm 2.

The parts remain in this position until the temperature in the room has increased to an extent that the differential expansion of the member 3 causes the lower end thereof to swing to the left across and well past the longitudinal center line of the lever 2. As the spring 14 is thus shifted so that its axis crosses the longitudinal center line of the lever arm 2, the resiliency of the spring urges the arm to open the switch and finally causes the lever arm to suddenly swing to the left and thereby quickly disengage the electrodes 4 and 5. Gravity supplemented by friction, as at 10, retards the opening until the thermostat tip reaches a point well past the neutral axis or center line of lever 2 whereupon these retarding influences are suddenly overbalanced and the switch flies open. The breaking of the circuit stops the control device and checks the operation of the heating plant.

The parts remain in this shifted position until the room temperature decreases sufficient to react upon the member 3 and cause it to shift back into the position shown in Figure 1, whereupon the lever arm 2 is shifted to reengage the electrodes 4 and 5 and again close the circuit.

The operation of the modification shown in Figure 4 is the same, except that the shifting of the member 3 is accomplished by pressure acting on the diaphragm device 32. Both forms shown are covered by the claims.

Although but two embodiments of this device have been herein shown and described, it will be understood that still other modifications for accomplishing the same purpose may be developed and numerous details of the modifications herein shown may be altered or omitted without departing from the spirit of the invention, as defined in the following claims.

I claim:

1. A thermostat comprising a base plate, a lever arm pivoted at one end to said plate to have a limited swinging movement, a stop to limit the swing of said arm a pair of electrodes, one carried on said lever arm and the other mounted on said plate in position to engage with the electrode on said lever arm, an automatically actuated member mounted on said plate and arranged substantially in longitudinal alinement with

said lever arm and connected at one end to said plate, and a helical spring connecting the other end of said member with said lever arm at a point remote from its pivotal connection to said plate, said spring being disposed in tension nearly in alinement with the end of said member said spring having a stiffening rod embraced therein but unconnected to said spring, member or lever arm and said stop being arranged to frictionally oppose the swing of said spring and rod.

2. A thermostat comprising a base plate, a lever arm pivotally suspended on said plate to have a limited swinging movement in a plane parallel to that of said plate, a pair of electrodes, one carried on said lever arm and the other mounted on said plate in position to engage with the electrode on said lever arm, said lever arm being nor-

mally urged to engage said electrodes, said lever arm having a transversely disposed slot formed therein, a pin on said plate extending into said slot and adapted to coact therewith to limit the swinging movement of said lever arm, an automatically actuated member arranged on said plate substantially in longitudinal alinement with said lever arm, and connected at one end to said plate remote from said lever arm, a resilient connection between the other end of said member and the other end of said lever arm and said connection being arranged to frictionally ride upon said pin upon opening the contact of said electrodes, whereby the opening is retarded and snap action is assured.

Signed at Chicago this 15th day of Nov., 1922.

JEFFERSON C. GIBSON.
